UNITED STATES PATENT OFFICE.

JAMES QUINN, OF MONTREAL, QUEBEC, CANADA.

FARE-BOX.

940,727.

Specification of Letters Patent. Patented Nov. 23, 1909.

Application filed April 19, 1909. Serial No. 490,790.

To all whom it may concern:

Be it known that I, JAMES QUINN, of the city of Montreal, Province of Quebec, Canada, have invented certain new and useful 5 Improvements in Fare-Boxes; and I do hereby declare that the following is a full, clear, and exact description of the same.

My invention relates particularly to the means for preventing the fraudulent withdrawal of fares from a fare box through the fare slot, and it has for its object to provide means for the purpose which will be more durable and more difficult to tamper with successfully.

15 The invention may be said briefly to consist of the several combinations and arrangements of parts hereinafter described and pointed out in the claims.

For full comprehension, however, of the 20 invention reference must be had to the accompanying drawings forming a part of this specification, in which similar reference characters indicate the same parts and wherein:

25 Figure 1 is a longitudinal sectional view of the top of a fare box with my invention applied thereto; Fig. 2 is a plan view of the underside of the top plate removed and provided with my invention; Fig. 3 is a detail 30 plan view of the top side of my improved tooth carrying plate; Fig. 4 is a detail perspective view of one of the teeth, removed; Fig. 5 is a detail longitudinal sectional view of a portion of the box top and illustrating 35 one of the teeth in its extreme depressed position; Fig. 6 is a similar view with the tooth in its normal position; and Fig. 7 is a detail perspective view of one of the teeth carrying plates with all the teeth and 40 springs, except one, removed.

The fare box *b* is of usual construction and provided with a removable top plate *c* having a transverse fare slot *d* therein. A pair of members *f* are fastened to the underside of the top plate and have mounted therein a plurality of movable interdigitating teeth *g* so constructed and mounted that their movement is limited by the top plate while the springs *h* for yieldingly resisting 45 the movement are located between the carrying members and top plate and thus protected from damage when the coins in the box are shaken about. The carrying members I prefer to use each consists of a plate 50 having a plurality of notches *k* (Fig. 7) in

one edge and inclined recesses *m* diminishing in depth from the notches toward the opposite edge of the plate. The teeth have their butts beveled as at *n* and they are pivoted at their butts on a common hinge pin *o* 60 bearing in the fingers *p* presented between the notches *k* and passing through perforations in the teeth. The springs *h* are flat and countersunk in the recesses and fastened in the shallow ends of the recesses by 65 drops of solder, while their free ends bear upon the beveled butts of the teeth.

Although I have described my means for preventing tampering applied to a fare box the essential features thereof may be used in 70 conjunction with any receptacle having an opening to be protected, without departing from the spirit of my invention.

What I claim is as follows:

1. The combination with a receptacle having an opening, of a plurality of teeth within the receptacle and fulcrumed at the sides of the opening with their points intersecting the said opening, and a spring resisting the movement of the teeth and located between 80 the teeth and the side of the receptacle having the opening therein.

2. The combination with a receptacle having an opening, of a plurality of teeth disposed at opposite sides of the opening with 85 their points intersecting the opening at the inner side thereof, means supporting the teeth in close proximity to the side of the receptacle having the opening therein, and a plurality of springs between the said 90 means and the said side of the receptacle and bearing upon the butts of the teeth.

3. The combination with a receptacle having an opening, of a plurality of teeth within the receptacle at opposite sides of the opening and each having one end pointed and its opposite end or butt beveled, means pivotally supporting such teeth with their points intersecting the opening and a plurality of springs located between the said 100 means and the side of the receptacle having the opening therein and bearing upon the beveled butts of the teeth.

4. The combination with a fare box having a slot for the introduction of the fare, of a plurality of teeth disposed at opposite sides of the slot with their points intersecting the opening at the inner side of the slot, means supporting the teeth in close proximity to the slotted side of the box, and a 110

plurality of springs between the said means and the said slotted side of the box and bearing upon the butts of the teeth.

5. The combination with the slotted top of a fare box, of a plurality of teeth within the box at opposite sides of the slot and each having one end pointed and its opposite end or butt beveled, means pivotally supporting such teeth with their points intersecting the slot and a plurality of springs located between the said means and the top of the box and bearing upon the beveled butts of the teeth.

6. The combination with a fare box having a slot for the introduction of the fare, of a plurality of teeth fulcrumed at the sides of the slot with their points intersecting the opening at the inner side of the slot, and a plurality of springs located between the teeth and the top of the box and resisting the movement of the teeth.

7. The combination with the slotted top of a fare box, of a pair of plates fastened

to the inside of the said top one at each side of the slot, such plates having their adjacent edges notched and their sides contiguous to the top of the box formed with recesses communicating with the notches and diminishing in depth from the said notches toward the opposite side edges of the plates, a plurality of teeth pivotally mounted in the notches with their points interdigitating and their butts beveled and adapted when the teeth are in abnormal position to bear upon the inside of the top of the box, and a plurality of springs located and secured at one end in the recesses and bearing upon the beveled butts of the teeth.

In testimony whereof, I have signed my name to this specification, in the presence of two subscribing witnesses.

JAMES QUINN.
